UNITED STATES PATENT OFFICE.

EDWARD R. SARGENT, OF NEW HAVEN, CONNECTICUT, ASSIGNOR TO SARGENT & COMPANY, OF NEW HAVEN, CONNECTICUT, A CORPORATION OF CONNECTICUT.

CHEST-HANDLE.

1,094,820.

Specification of Letters Patent. Patented Apr. 28, 1914.

Application filed February 10, 1914. Serial No. 817,833.

To all whom it may concern:

Be it known that I, EDWARD R. SARGENT, a citizen of the United States, residing in the city and county of New Haven, State 5 of Connecticut, have invented certain new and useful Improvements in Chest-Handles, of which the following is a full, clear, and exact description.

This invention relates to chest handles, 10 and the primary object which I have in view is the provision of a strong, durable handle which can be manufactured readily and at a low cost.

To this and other ends, the invention consists in the novel features and combinations 15 of parts to be hereinafter described and claimed.

In the accompanying drawing, Figure 1 is a front elevation of a chest handle embodying my improvements with the bail in 20 the pendant position; Fig. 2 is an end view of Fig. 1; Fig. 3 is a rear view of the handle with the major portion of the bail omitted; Fig. 4 is a fragmentary end elevation 25 showing how the plate and bail are assembled; and Fig. 5 is a fragmentary rear end of Fig. 4.

Referring to the drawing, the attaching plate 10, having the screw holes 11, is preferably made of a sheet metal blank having 30 a horizontally directly forwardly bulged socket portion 12. This socket portion 12 terminates short of the respective ends of the plate and merges into shoulders 13 at the 35 ends of the plate. These shoulders are located above the openings 14 at the ends of the socket portion 12. The bail consists of hanger arms 15, engaging the respective openings 14 of the socket portion 12, and a 40 grip portion 16 having end sockets 17 fitting over the lower terminals 15^a of the hanger arms. In manufacturing the device, the portions of metal 10^a at the respective ends 45 of the plate beyond the extremities of the socket portion 12 are provided with longitudinal grooves 18, as shown in Fig. 4, formed by indenting the metal from the front of the plate. This creates a rib 19 on the back of the plate, as shown in Fig. 5. 50 Each groove 18 is preferably in approximate horizontal alinement with the center of the corresponding opening 14, and is adapted to clear a wing or lug 20 on the upper extremity 15^b of the corresponding hanger arm. The hanger arms are raised into a

horizontal position, as shown in Fig. 4, so that the wings or lugs 20 will pass through the grooves 18 and permit the end portions 15^b to enter the socket portion 12 to the necessary extent. In the meantime, the lower end portions 15^a of the respective arms are properly assembled relative to the grip 16. The bail when thus assembled may then be permitted to drop into the position shown in Fig. 2, and the projections 19 are 60 then hammered out by a suitable tool so as to confine the hanger arms permanently in the socket 12. In other words, the groove 18 is flattened out, and the metal portions 10^a at the ends of the plate are so displaced 65 as to block movement of the corresponding wings or lugs 20 in an outward direction relative to the socket, as will be understood.

When the handle is in use, the upper ends of the arms 15 abut the shoulders 13, which 70 form abutments for the bail in the elevated position of the latter. The grip 16, being free to turn relatively to the hanger arms, does not turn in the hand when the bail is raised. The wings or lugs 20 on the ends 75 of the hanger arms in engaging the portions 10^a of the plate effectively prevent outward displacement of the respective arms in 80 respect to the corresponding sockets of the plate and grip.

Without limiting myself to the construction shown, I claim:

1. In a chest handle, the combination of an attaching plate having a forwardly bulged socket open at the end, said plate 90 having a transverse portion adjacent the mouth of said socket, and a hanger arm at the front of the plate entering said socket in front of said transverse portion, and provided with a wing or lug adapted to engage 95 said transverse portion, whereby said hanger arm is retained in said socket; substantially as described.

2. In a chest handle, the combination of an attaching plate having a socket portion 100 bulged forwardly from the plate and open at the respective ends, said ends of said socket portion terminating short of the ends of the plate, and the latter being provided with portions of metal adjacent the socket 105 ends, separate hanger arms having upper ends located in the openings of the socket portion, means to prevent dislocation of said ends of the hanger arms relative to said socket portion, and a grip member having 110

sockets at the respective ends in which the lower ends of the respective hanger arms are freely rotatable; substantially as described.

3. In a chest handle, the combination of 5 an attaching plate having a horizontally directly forwardly bulged socket portion open at the respective ends, said plate having metal portions at the ends adjacent the respective ends of said socket portion, a bail 10 comprising hanger arms entering said socket portion at the respective ends, and lugs on said hanger arms blocked against outward displacement relative to the socket portion by engagement with the aforesaid portions 15 of the plate adjacent the ends of the socket; substantially as described.

4. In a chest handle, an attaching plate having sockets facing toward the respective ends of the plate, a grip member, separate 20 hanger arms having their upper ends extending into said sockets and their lower ends rotatably connected with said grip member, and interengaging means on the hanger arms and attaching plate respectively 25 for preventing outward displacement of each hanger arm relative to its socket; substantially as described.

5. In a chest handle, an attaching plate having sockets facing toward the respective 30 ends of the plate, a grip member, separate hanger arms having their upper ends extending into said sockets and their lower ends rotatably connected with said grip member, and interengaging means on the 35 hanger arms and attaching plate respectively for preventing outward displacement of each hanger arm relative to its socket, said means comprising a lug on the upper end of each hanger arm and a transverse 40 portion on the plate to coöperate with said lug; substantially as described.

6. In a chest handle, an attaching plate having sockets facing toward the respective ends of the plate, separate hanger arms having their upper ends extending into said 45 sockets, means to retain the upper ends of said hanger arms in said sockets, and a grip member connecting the lower ends of said hanger arms and freely rotatable with respect to said arms; substantially as de- 50 scribed.

7. In a chest handle, an attaching plate having sockets facing toward the respective ends of the plate, a grip member having 55 sockets in the respective ends thereof, separate hanger arms having their upper ends extending into the sockets of the plate, and their lower ends extending into the sockets of the grip member, and means for preventing dislocation of the hanger arms relative 60 to the plate and grip member; substantially as described.

8. In a chest handle, an attaching plate having sockets facing toward the respective ends of the plate, a grip member having 65 sockets in the respective ends thereof, separate hanger arms having their upper ends extending into the sockets of the plate, and their lower ends extending into the sockets of the grip member, and means for preventing 70 dislocation of the hanger arms relative to the plate and grip member, comprising lugs on the hanger arms and coöperating lug-engaging portions on the attaching plate; substantially as described. 75

In witness whereof, I have hereunto set my hand on the 7th day of February, 1914.

EDWARD R. SARGENT.
